(57) **CLAIM**

The ornamental design for a lighting fixture as shown and described.

DESCRIPTION

FIG. 1 is a front and side perspective view of a first embodiment a lighting fixture showing the present design; FIG. 2 is a front and side perspective view thereof in a second position;

FIG. 3 is a side view thereof;

FIG. 4 is a front view thereof;

FIG. 5 is a rear view thereof;

FIG. 6 is a top view thereof;

FIG. 7 is a bottom view thereof;

FIG. 8 is a front and side perspective view of a second embodiment of a lighting fixture showing the present design; FIG. 9 is a front and side perspective view thereof in a second position;

FIG. 10 is a side view thereof;

FIG. 11 is a front view thereof;

FIG. 12 is a rear view thereof;

FIG. 13 is a top view thereof; and,

FIG. 14 is a bottom view thereof.

1 Claim, 14 Drawing Sheets
